UNITED STATES PATENT OFFICE.

GEORGE C. L. TISCH, OF ELIZABETH, NEW JERSEY, ASSIGNOR TO TISCH MACHINE DIE WORKS, OF ELIZABETH, NEW JERSEY, A CORPORATION OF NEW JERSEY.

PUSHER FOR KNITTING MACHINES.

Application filed May 19, 1923. Serial No. 640,148.

To all whom it may concern:

Be it known that I, GEORGE C. L. TISCH, a citizen of the United States, and a resident of Elizabeth, in the county of Union and 5 State of New Jersey, have invented a new and Improved Pusher for Knitting Machines, of which the following is a full, clear, and exact description.

This invention relates to knitting machines and particularly to an improved pusher therefore and has for an object to provide a pusher foot and associated mechanism which will act to cause the pins to be pushed more steadily and to thereby cause 15 them to accurately function.

Another object of the invention is to provide a pusher structure for what are commonly called flat or similar knitting machines wherein the pusher foot is arranged 20 to cause the pin operated thereby to more accurately move in its prescribed path.

In the accompanying drawings—

Figure 1 is a fragmentary front view of one side of a Tisch knitting machine, with 25 an embodiment of the invention applied thereto.

Figure 2 is a side view of the structure shown in Figure 1, illustrating the relative position of the pusher in respect to the jac- 30 quard links and pins.

Figure 3 is a perspective view of the pusher foot shown in Figure 2.

Figure 4 is a diagram showing the movement and action of the pusher foot in re- 35 spect to one of the jacquard pins.

Referring to the accompanying drawings by numeral, 1 indicates the frame of a knitting machine which is of the flat type and which is known on the market as a Tisch 40 knitting machine shown more or less in detail in Patent No. 457,265. This machine is provided with a plurality of jacquard links 2 and each link is provided with a plurality of pins 3. These pins are adapted to be pushed over and in turn shift the needle bars whereby different designs may be knit. The construction just described is old and well known and forms no part of the invention except in combination.

Associated with the pins 3 is a pusher lever 4 pivotally mounted at 5 on a suitable bracket 6. A link structure 7 is provided for swinging the lever 4 back and forth a predetermined distance on each 55 movement. The mechanism 7, lever 4 and

associated parts are old and well known and driven in a well known manner. Mounted upon the lever 4 is a pusher foot 8 which acts against the pin 3 and in combination with the parts above described, presents a 60 new construction for shifting the pins. The pusher foot 8 is also provided with a new construction of face 9 which is concave and the parts are so arranged with the con- 65 cave face 9 as to cause the center thereof to engage the end of pin 3 when the lever 4 has moved for about one-fourth its travel toward the frame 1.

As indicated in Figure 4, when the pusher foot 8 strikes the pin 3, the end of the pin 70 will strike the concave face 9 above a central line. As the parts move to the point 10, the shoe will slide relative to the pin until the end of the pin engages the center of the shoe when it reaches the position 10, as 75 shown in Figure 4. As the shoe continues to move to positions 11, 12 and 13, the shoe will move relative to the pin as indicated. When the shoe 8 first strikes the pin and moves toward the position 10, it will tend 80 to crowd the pin downwardly and cause the jacquard link carrying the pin to more snugly fit the sprocket wheel 14 so that the parts will be more accurately aligned and thereby the pin will more accurately engage 85 the thread bar which it is to move. Where the parts have been somewhat worn, this pressure on the pin to cause the same to hug the sprocket wheel 14 is very desirable as it results in a proper alignment of the parts 90 automatically. The downward pressure on the pin 3 produces a tension on the jacquard link or the jacquard chain structure and by reason of this, the slight movement caused by this tension, causes the link to 95 settle more accurately on the chain, and consequently, causes the pin to be more accurately moved as the machine operates.

What I claim is:

1. In a knitting machine provided with 100 thread bar shifting pins, a pusher lever, and a foot carried by the lever for shifting said pins, said foot being formed with a concave face.
2. The combination with a knitting ma- 105 chine provided with thread operating pins, and a pusher mechanism associated therewith, of a pusher shoe carried by the pusher mechanism, said shoe being formed with a face adapted to engage said pins so as to 110

cause the pins and parts associated therewith to become accurately aligned through the pressure on the pins.

3. In a knitting machine provided with bar shifting pins, a pusher foot provided with a flange for receiving securing means, a body extending substantially an equal dis-

tance on each side of the flange along one edge of the flange, said body having an arc-shaped concave face and means for forcing 10 said face against said pins for shifting the pins.

GEORGE C. L. TISCH.
